UNITED STATES PATENT OFFICE.

HENRY J. GRIMM, OF QUINCY, ILLINOIS.

COMBINED STEP AND EXTENSION LADDER.

Application filed March 26, 1923. Serial No. 627,686.

To all whom it may concern:

Be it known that I, HENRY J. GRIMM, a citizen of the United States, residing at Quincy, in the county of Adams and State 5 of Illinois, have invented certain new and useful Improvements in Combined Step and Extension Ladders, of which the following is a specification.

This invention relates to a combined 10 step and extension ladder and has for its principal object to provide a device which can be easily and quickly converted from a stepladder into an extension ladder and is furthermore provided with means for holding 15 the extension ladder in adjusted position.

Another important object of the invention is to provide a combined step and extension 20 ladder of the above mentioned character, which can also be used for the purpose of supporting a board or other suitable member used by paperhangers.

A still further object of the invention is to provide a combined step and extension 25 ladder of the above mentioned character wherein the stepladder is provided with suitable means for receiving and adjustably supporting an extension section thereon and whereby the extension section can be raised 30 or lowered to the desired height.

Another important object of the invention is to provide a combined step and extension 35 ladder which is simple in construction, inexpensive, strong, durable, and further well adapted for the purpose for which it is designed.

Other objects and advantages of this invention will become apparent during the course of the following description.

40 In the accompanying drawings forming a part of this specification and in which like numerals designate like parts throughout the same:—

Figure 1 is a side elevation of the ladder 45 when arranged for use as a step ladder.

Figure 2 is a central vertical section of the step ladder showing the same in extended position.

Figure 3 is a sectional view showing the 50 fastening means.

Figure 4 is a perspective view of the channel member.

Figure 5 is a plan view of the step ladder 55 showing the same used for supporting an elongated board.

Figure 6 is a side elevation of the device as shown in Fig. 5.

Figure 7 is a side elevation of the device 60 as shown in Figs. 5 and 6 showing the same in a folded position.

Figure 8 is a sectional view taken on line 8—8 of Fig. 2, and

Figure 9 is a sectional view taken on line 9—9 of Fig. 8.

In the drawings wherein for the purpose 65 of illustration is shown the preferred embodiment of my invention, the numeral 1 designates generally a step section which comprises the two side bars 2 and 3 and between which are supported the usual steps 70 3'. The upper ends of the side bars 2 and 3 respectively are provided with the plates 4 and 5 respectively and these plates 4 and 5 have their longitudinal sides flanged laterally to engage the side edges of the side 75 bars 2 and 3 and the plates 4 and 5 are further supported upon the inner faces of the side bars 2 and 3 by any suitable fastening means such as rivets or the like. The plates 4 and 5 are provided with apertures 6 and 7 respectively and these apertures 80 are arranged in the form of an arc and in spaced relation for the purpose hereinafter to be more fully described. It is to be further understood that the side bars 85 2 and 3 are also to be provided with apertures formed by punching the apertures in the plates 4 and 5. However, the apertures formed in the side bars 2 and 3 which register with the apertures 6 and 7 extend only 90 a suitable distance into the side bars 2 and 3.

Pivotedly mounted upon the upper ends of the side bars 2 and 3 and arranged upon the inner faces of the plates 4 and 5 are a pair 95 of channel members 8 and 9 respectively. As both of the channel members 8 and 9 are of the same construction, it is deemed only necessary to describe one of them as the description of one is thought to suffice for both. Each channel member is provided 100 with an aperture 11 arranged centrally therein for the purpose of receiving the bolt 11' which passes through the upper end of the side bar and through the plate for pivotally supporting the channel members on the plates and upper ends of the side bars. A suitable nut or other fastening means is 105 adapted to be threaded upon the inner end of the bolt 11' as indicated at 12 for the purpose of preventing the accidental dis- 110

placement or removal of the channel members from the upper ends of the side bars,

The channel members 8 and 9 respectively are adapted to receive and support therein 5 the side bars 13 and 14 respectively of the extension section 15 which is provided with the usual spaced rungs 16 between the side bars in the well known manner. It will be noted that the side bars 13 and 14 of the 10 extension section 15 are adapted to slide in the channel members 8 and 9 for the purpose of holding the extension section in the desired position. The channel shaped members 8 and 9 are provided with set screws 17 15 for engagement with the edges of the side bars 13 and 14 whereby the extension section 15 is held in its adjusted position.

The lateral extension 10 of each of the channel members 8 and 9 is provided with 20 a pivoted spring catch 18 and the spring catch is pivotally mounted on the bolt 11 and is held thereon by the fastening nut 12. The spring catch 18 has its free end extending beyond the side edge of the lateral extension 10 and is provided with a projection 19 extending through a suitable aperture 20 formed upon the spring catches 18 are lateral extension 10. The projections 19 formed upon the spring catches 18 are 25 adapted to register with and fit into the apertures 6 and 7 formed in the plates 4 and 5 for the purpose of holding the channel members 8 and 9 in various adjusted positions as will hereinafter be more fully described. The purpose of having the free end 21 of the spring catch 18 extend beyond the edge of the channel members is to provide a suitable handle whereby the projection 19 may be disengaged from the various apertures for the purpose of swinging the channel members upon the upper ends of the side bars 2 and 3 whenever it is desired.

It will be seen from the drawings in Fig. 1 wherein a side elevation is shown that the 45 extension section 15 in this position acts in the capacity of supporting legs for the step section 1 and the inclination of the step section 1 may be adjusted by releasing the set screws 17 from engagement with the side bars 13 and 14 of the extension section whereby the same may be slid in the channel members 8 and 9 so as to either raise or lower the step section 1. It will be further noted that the 50 spring catch and the projection carried thereby will fit in one of the apertures formed in each of the plates 4 and 5 for holding the step section 1 and extension section 15 in the adjusted position and thereby prevent the accidental movement of either 55 of the step section 1 or the extension section 15 when in use.

When it is desired to use the extension section 15 for the purpose of placing the same against a building as is customary 60 with a ladder of great length, I accomplish

this feature by swinging the extension section 15 and the channel members 8 and 9 upon the pivot bolt 11 in such a manner that the bottom beveled edges or legs of the extension section 15 rest upon the top step 70 of the section 1 and when in this position as more clearly shown in Fig. 2 of the drawings, the extension section will be in the same plane with the step section 1 and after the extension section 15 has been swung into 75 its proper position upon the upper end of the step section 1 it will be seen that the legs of the extension section 15 are supported within the channel members 8 and 9 and are held in this position by the set screws 80 17. The spring catch 18 and the projection 19 carried thereby will further aid in supporting the extension section in its proper adjusted position upon the step section 1 as heretofore described.

As shown in Figs. 5 and 6 of the drawings wherein the step section 1 and the extension section 15 are used for the purpose of supporting a board 22 which is used by paperhangers or the like, the extension section 15 is adjusted in the channel members 8 and 9 by the above described means arranged in the position as shown in the drawings in Figs. 5 and 6 and when in this position the auxiliary legs 23 and 24 which 90 are pivotally mounted at their upper ends to the sides of the side bars 2 and 3 will be caused to swing outwardly from the side bars so that their bottom ends rest upon the ground in the manner as shown and for the 95 purpose of preventing the step section 1 and extension section 15 from collapsing I provide the stop members 25 upon the side bars 2 and 3 adjacent the upper ends of the auxiliary legs 23 and 24. In this manner the 100 auxiliary legs 23 and 24 are limited in their movement in one direction and thereby will prevent the accidental collapsing of the ladder. It is to be further understood that the 105 board 22 is held between the side bars 13 110 and 14 of the extension section in the manner as shown more clearly in Figs. 5 and 6 of the drawings.

It will thus be seen from the foregoing description that a combined step and extension 115 ladder has been provided wherein a ladder may be extended for use as a scaling ladder and may also be adjusted for uses for various other purposes. It is to be further noted from the above description that 120 a construction of the character described a ladder may be easily and quickly collapsed whereby the same may be more readily and easily handled and does not require the use of a number of tools for the purpose of setting up the ladder for use and the simplicity of the device further renders the same 125 very efficient and useful in its operation.

From the foregoing description of the 130 construction of my improved apparatus, it

will be seen that I have provided a simple, inexpensive and efficient means for carrying out the objects of the invention, and while I have particularly described the elements best adapted to perform the functions set forth, it is obvious that various changes in form, proportion and in the minor details of construction may be resorted to, without departing from the spirit or sacrificing any 10 of the principles of the invention.

What I claim as new and desire to secure by Letters Patent is:—

1. A device of the character described, comprising a pair of ladder sections, plates 15 carried by the upper ends of the side bars of one of the sections, channel shaped members formed with longitudinally extending lateral extensions having pivotal connection with the plates, the other section being slidably received in the channel shaped members, resilient latch elements pivoted to the 20 longitudinally extending lateral extensions

and cooperating with said plates in holding the last-mentioned ladder section in adjust- 25 ed position.

2. In a device of the character described, a pair of ladder members, one of which is provided with a plate at the upper end of each side bar thereof, channel members each provided with a lateral extension for pivot- 30 ally mounting said channel members on said plates, said plates provided with spaced apertures, said channel members adapted to receive the side bars of the other ladder, means for holding the latter in said channel 35 members, and a pivoted catch carried by said lateral extension and provided with a projection for engagement with the apertures formed in said plate for adjustably holding the channel members and said sec- 40 ond mentioned ladder on the upper end of the first mentioned ladder.

In testimony whereof I affix my signature.

HENRY J. GRIMM.
